(57) CLAIM

The ornamental design for a golf club head, as shown and described.

DESCRIPTION

FIG. 1 is a bottom perspective view of a golf club head.

FIG. 2 is a top perspective view of the golf club head of FIG. 1.

FIG. 3 is a bottom view of the golf club head of FIG. 1.

FIG. 4 is a top view of the golf club head of FIG. 1.

FIG. 5 is a left side view of the golf club head of FIG. 1.

FIG. 6 is a right side view of the golf club head of FIG. 1.

FIG. 7 is a front view of the golf club head of FIG. 1; and,

FIG. 8 is a back view of the golf club head of FIG. 1.

In each of the Figures, broken lines show elements that form no part of the claimed design.
